Primary Examiner — Samantha Wood*Assistant Examiner* — Emily A Caven(74) *Attorney, Agent, or Firm* — Mandana Jafarinejad(57) **CLAIM**

The ornamental design for a portable poop scooper, as shown and described.

DESCRIPTION

FIG. 1 is a perspective view of a portable poop scooper showing my new design in an open scoop configuration; FIG. 2 is a front view of a portable poop scooper in a closed scoop configuration;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front view of a portable poop scooper shown in a use state with poles extended from their housings; and, FIG. 9 is a front view of a portable poop scooper shown in an alternate configuration, with poles in a portable/bent use state position.

Broken lines in the drawings depict portions of the portable poop scooper that form no part of the claimed design.
